UNITED STATES PATENT OFFICE.

PATRICK J. BOHAN, OF SAN DIEGO, CALIFORNIA, ASSIGNEE OF ONE-HALF TO J. E. FRAZER, OF SAN DIEGO, CALIFORNIA.

GAS BURNER.

1,415,141.

Specification of Letters Patent. Patented May 9, 1922.

Application filed March 8, 1920. Serial No. 364,000.

To all whom it may concern:

Be it known that I, PATRICK J. BOHAN, a citizen of the United States, residing at San Diego, in the county of San Diego and State of California, have invented a certain new and useful Gas Burner, of which the following is a specification.

My invention relates to a gas burner more particularly adapted for use where a great many heat units are required such as heating boilers and the like and the objects of my invention are: First, to provide a burner of this class in which the gas contacts with a disk shaped baffle plate for spreading the flame which baffle plate is adjustable relatively to the outlet of the gas or near the point of ignition; Second to provide a gas burner of this class in which the baffle plate will not overheat and will distribute the flame as desired by adjustment; Third, to provide a burner of this class which consists largely of standard fittings; Fourth, to provide a burner of this class which is very efficient in its action and which will not readily deteriorate or get out of order and Fifth, to provide a burner of this class which is very simple of construction, durable, easy to operate, and easy to install.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a side elevational view of my burner showing some of the parts and portions broken away and in section to facilitate the illustration: Fig. 2 is a plan view of a fragmentary portion thereof and Fig. 3 is a fragmentary side elevational view in a slightly modified form from that of Fig. 1, showing some of the parts and portions broken away and in section.

Similar characters of reference refer to similar parts and portions throughout the several views of the drawings.

The baffle-plate 1, baffle-plate support 2, gas distributor 3, T-member 4, nipple 5, base 6, pipe 7, Y-member 8, reducer plug 9, nozzle 10, gas conducting pipe 11, and

valve 12, constitute the principal parts and portions of my gas burner in the preferred form.

The baffle-plate 1 is a disc shaped metallic member of suitable size for the size of the burner and proper distribution of the blaze and it is provided with a central hole which is threaded adapted for the one end of the supporting bolt 2 and fits tightly thereon. The other end of this supporting bolt 2 is also threaded and adapted to screw into a central hole in the spider 3^a on the interior of the gas distributing member 3 thus providing for the adjustment of the baffle-plate 1 relatively to the upper end of the gas distributing member 3 by turning the baffle-plate. This member 3 is bell shaped at its upper end to provide for the unretarded flow of the gas between its upper edge and the baffle-plate 1. This member 3 is threaded on its lower end and screwed into the T-member 4, the opposite portion of the T-member connects with the nipple 5 which is supported in a convex disc shaped member 6 forming a support for the burner. Extending from the right angle portion of the T-member 4 and communicating therewith is the pipe 7, upon the end of which is secured the Y-member 8. In the end of the straight portion of which is mounted a reducing plug 9 in the small portion of which is mounted a nozzle 10, which extends in through the Y-member and part way into the pipe 7. In the larger hole in the plug member 9 is secured the conductor 11, which is provided with a valve 12 for regulating and controlling the flow of gas to the burner.

In operation the gas passes through the conductor 11 through the nozzle 10 into the pipe 7 and air passes through the portion 8^a of the Y-member 8 and the two are carried upwardly through the member 3, striking the baffle-plate and then outwardly around the outer edge of the baffle-plate.

In the modified form of construction shown in Fig. 3 of the drawings the structure is the same except that connecting with the conductor 11 is a compressed air tank 13, shown fragmentarily in said Fig. 3 and air only passes through this conductor 11 and valve 12 and nozzle 10, which is air under pressure from the tank 13 while the gas passes from the conductor 14, regulated by a valve 15 and is carried with the air to

the burner. The structure shown in Fig. 3 being used where the gas is not delivered from a gas retort or under pressure.

Though I have shown and described a particular construction, combination and arrangement of parts and portions and a certain modification thereof, I do not wish to be limited to this particular construction, combination and arrangement nor the modification thereof, but desire to include in the purview of my invention the construction, combination and arrangement substantially as set forth in the appended claims.

It is obvious that with this construction there is provided a burner in which gas is delivered to the baffle-plate under pressure, carrying with it a suitable proportion of air; that the baffle-plate may be readily adjusted relatively to the outlet of the gas distributor 3 to provide the greatest efficiency and proper distribution of the blaze.

Having thus described my invention, what I claim as new and desire to secure by Letters Patent, is:

25. 1. A gas burner, including a fuel conducting pipe in L-shape, a fuel distributing

nozzle extending some distance into the inlet end of said fuel conducting pipe and an air inlet communicating with said conducting pipe from one side only and back of the 30 end of the distributing nozzle and a flat baffle-plate adjustably mounted over the outlet end of said conducting pipe.

2. A gas burner, including an L-shaped conducting pipe, a flange support therefor, 35 a fuel distributing nozzle mounted in the inlet end of said conducting pipe and extending some distance therein, an air inlet communicating with the exterior of said distributing nozzle intermediate its ends, a 40 spider mounted in the opposite end of said conducting pipe, a pin screwed into said spider centrally therein and a flat baffle-plate screwed onto the extended end of said pin spaced from the outlet end of said conducting pipe, and a base for supporting said conducting pipe.

In testimony whereof, I have hereunto set my hand at San Diego, California, this 28th day of February 1920.

PATRICK J. BOHAN.
